ELECTRICAL GAUGE

George L. Garvin, South Bend, Ind.

Application March 24, 1943, Serial No. 480,301

12 Claims. (Cl. 33—172)

This invention relates to improvements in electrical gauges, such as comparators.

The primary object is to provide a device of this character which is simple in construction, sensitive, accurate, and comparatively inexpensive.

A further object is to provide a device of this character utilizing variations in an iron-closed alternating current coil produced by shifting a movable armature by means of a touching pin, to vary the current flow in a circuit including a rectifier in series therewith, and a measuring instrument connected with said rectifier.

A further object is to provide a device of this character wherein a condenser is employed to increase the sensitivity of the instrument.

A further object is to provide a device of this character with novel electrical means for adjusting the calibration thereof.

A further object is to provide a device of this character with novel electrical means for zero-adjustment of the device.

A further object is to provide a device of this character having a choke-coil-controlled circuit including a rectifier, and a zero-adjustment circuit for applying to a measuring instrument connected with said rectifier a rectified counter E. M. F. of selected value.

A further object is to provide a device of this character having a novel, simple and compact construction and relation of choke coil, touching pin, associated control elements and housing.

A further object is to provide a device of this character wherein the choke coil, touching pin and associated elements are preassembled as a unit for easy, quick and simple introduction into and mounting within a housing therefor.

In the drawing—

Fig. 1 is a diagrammatic view of the basic circuit utilized in the device.

Fig. 2 is a diagrammatic view of a circuit including calibrating means, zero-adjustment means, and sensitivity increasing means.

Fig. 3 is a longitudinal sectional view taken on line 3—3 of Fig. 4, illustrating the construction of the touching unit.

Fig. 4 is a transverse sectional view taken on line 4—4 of Fig. 3.

Fig. 5 is a transverse sectional view taken on line 5—5 of Fig. 3.

Fig. 6 is an enlarged fragmentary detail sectional view.

Referring to the drawing, and particularly to Fig. 1 which illustrates the basic circuit utilized in the device, the numerals 10 and 11 designate

lines connected with a source of alternating current. A step-down transformer 12 has a primary coil 13 connected across lines 10—11, and a secondary coil 14. A conductor 15 connects one end of secondary coil 14 with a coil 16 wound around one leg of a laminated U-shaped stationary armature 17 with which is associated movable armature 18 normally spanning the ends of the legs of said first armature and adapted to be shifted into spaced relation by a touching pin 25. A conductor 19 connects coil 16 with one A. C. terminal of a rectifier 20. Rectifier 20 is of the full wave type. The other A. C. terminal of rectifier 20 is connected by conductor 21 with transformer secondary coil 14. A milliammeter 22 is connected to the D. C. terminals of rectifier 20 by conductors 23 and 24. Movable armature 18 is so connected with feeler pin 25 that deflection of said pin shifts the same away from stationary armature 17 thus decreasing the flux, induction and counter E. M. F. of self-induction of the coil, with resultant change in the flow of current which is measured in the meter 22. Meter 22 may be calibrated in terms of distance of deflection or movement of said touching pin. I have found that satisfactory results are obtained by using a transformer 12 having an output of approximately 10 volts, a coil 16 having a D. C. resistance of approximately 5000 ohms and a copper oxide full wave rectifier 20.

In Fig. 2 is illustrated a circuit as above described in which certain added features are incorporated. In this circuit a condenser 26 is interposed in conductor 19 in series with and between coil 16 and rectifier 20. I have found that when this condenser is properly selected with relation to coil 16, the sensitivity of the device is greatly increased. Thus the deflection of the meter for a given spacing of movable armature 18 from armature 17 is much greater when condenser 26 is employed than when it is omitted. The sensitivity of the device is increased further by connecting a second condenser 27 in parallel with coil 16 and condenser 26 by means of conductors 28. I have found that condensers 26 and 27 having capacities of .25 and .1 microfarad respectively produce satisfactory results when used with a core 17 and a coil 16 having a D. C. resistance of approximately 5000 ohms.

Calibration adjusting means may be incorporated in the circuit in conductor 21, and may comprise a variable resistance 29. Adjustment of the resistance varies the deflection of meter 25 for any given spacing of armature 18 from armature 17, to permit adjustment of the circuit to

correspond with the calibration of said meter. Where meter 22 is very delicate, a variable shunt 30 may be connected across conductors 19 and 21. This variable shunt can also be adjusted for calibration purposes.

Zero-adjustment of the meter 22 is effected electrically by imposing upon the meter a rectified counter electromotive force. Thus a second transformer 31 has its primary coil 32 connected across lines 10—11, and its secondary coil 33 is connected by conductors 34 with the A. C. terminals of a rectifier 35. The positive D. C. terminal of rectifier 35 is connected by conductor 36 with lead 24 connected with the negative D. C. terminal of rectifier 20. The negative D. C. terminal of rectifier 35 is connected by conductor 37 with lead 23 connected with the positive D. C. terminal of rectifier 20. A variable resistance 38 is interposed in conductor 37. By adjusting resistance 38, the current leakage of coil 16 can be accurately counterbalanced to insure positive and immediate return of the meter to zero.

The construction of the touching unit, i. e., coil, armature, touching pin, associated parts, and mounting therefor, is illustrated in Figs. 3 to 5. A rigid annular member 40 has a pair of diametrically opposed longitudinal grooves formed therein parallel to the axis thereof. A narrow, flat, elongated base plate 41 has one end thereof fitting snugly in one of said grooves and is fixedly secured to member 40 at 42. Plate 41 is of a thickness slightly less than the depth of the side walls of the groove receiving it, whereby its full outer surface is spaced from the axis of member 40 a distance not greater than the outer radius of member 40. The free end portion of the base plate 41, from a point 43 spaced from member 40, is of reduced width. The laminated U-shaped armature 17 is fixedly mounted on the reduced width portion of plate 41, as by means of a clip 44 of U-section fitting around said plate with its base 45 secured to said plate and its arms 46 engaging and secured to opposite sides of said armature 17. The opposite legs of armature 17 extend perpendicular to plate 41 and are of a length less than the diameter of member 40. Coil 16 encircles one of said armature legs.

In outwardly spaced relation to armature 17, plate 41 is provided with an aperture in which is fixedly secured a reduced neck portion 47 of a rigid tubular member or sleeve 48 extending perpendicular to plate 41. An elongated pin 25 is keyed to and slidable in sleeve 48. Pin 25 projects from the inner or free end of a sleeve 48 and terminates in a rounded end 49. A circumferential groove is formed in the projecting portion of pin 25 and receives a split ring 50 normally spaced from the end of sleeve 48 but engageable therewith to prevent withdrawal of the pin from said sleeve in the direction of plate 41. The outer end of pin 25 has a concentric threaded longitudinal bore 51 into which the shank 52 of a touching element or head 53 having a rounded outer end 54 is screw threaded to secure said parts together with head 53 in firm abutment with the end of pin 49. Head 53 may be milled to facilitate its application to pin 25 by a wrench.

A lever 56 in the nature of a narrow, elongated, flat plate similar to base plate 41, has one end thereof seated in the other groove of member 40 and secured thereto at 57. Lever 56 is also of a thickness slightly less than the depth of the side walls of the groove receiving same. The faces of plate 41 and lever 56 lie in substantially parallel planes. At a point opposite core 17 and substan-

tially centered relative thereto, lever 56 is provided with an aperture or hole 58 which is countersunk at its outer end at 59. A spacer block 60 has a pin 61 projecting centrally from one end thereof and passing through a central aperture in laminated movable armature plate 18. The outer end of pin 61 is swaged at 62 to form a head riveting said armature plate and spacer together. The opposite end of spacer 60 has a rounded surface 63, and a pin 64 projects centrally therefrom. Pin 64 is of a diameter smaller than aperture 58 into which it projects. Consequently, during assembly, the parts may be placed in operative relation, with plate 18 bearing flat on the ends of the legs of armature 17, with pin 64 in hole 58, and with plates 41 and 56 in normal and unflexed position, and solder 65 can then be applied at the countersunk mouth 59 of hole 58 without disturbing said operative relation, for the purpose of securely anchoring spacer 60 to lever 56. The free outer end of lever 56 projects outwardly past the sleeve 48 and pin 25, and the ring 50 on pin 25 holds said pin adjacent the inner face of said lever.

The construction above described, including annular member 40, base plate 41, lever 56, armatures 17 and 18, coil 16, sleeve 48, and pin 25 (but not head 53) is preferably preassembled as a unit, with conductors 15 and 19 passing through the bore of annular member 40. This preformed unit is then inserted in a tubular housing 66 preferably having an inner diameter snugly and slidably receiving member 40. The unit is secured in operative position in the housing by screws 67 securing the annular member 40 to the housing. Housing 66 has a hole 68 formed therein concentric with pin 25, through which touching head 53 may be inserted for threaded connection of its shank 52 with the bore of pin 25. When operatively secured to pin 25, only the rounded end 54 of head 53 preferably projects from the housing. At a point intermediate hole 68 and annular member 40, the housing is provided with a screw threaded hole receiving a set screw 69 perpendicular to and bearing against the outer face of base plate 41. Set screw 69 constitutes a mechanical zero-adjustment for the device. Housing 66 may be mounted upon any suitable standard (not shown) juxtaposed to surface plate (not shown) of a comparator or other device for measuring external dimensions, as is well understood in the art, or may be mounted on a handle (not shown) and provided with an accurately machined contact surface diametrically opposite the feeler pin hole 68 when used for measuring internal dimensions.

The unit mounting of the device in its housing provides only a slight clearance between the opposite outer longitudinal edges of plate 41 and lever 56 and the inner periphery of tubular housing 66. However, since the device is intended only for accurate measurement of small deflections of the touching pin, usually not greatly exceeding .005 inch, this small clearance is ample. However, if greater clearance is desired, the same can be obtained by increasing the depth of the grooves in member 40, or by reducing the width of the portions of plate 40 and lever 56 which project from member 40. It will be understood that the touching unit is used in a manner to entail inward movement of pin 25 and flexing of lever 56, with resultant movement of the movable armature 18 into spaced relation to armature 17. An air gap in the normal closed iron core 17—18 is thus provided which reduces the magnetic field

or flux and thereby alters the inductance in coil 16, so that by proper calibration of meter 22, the extent of movement of touching pin can be read upon said meter. Scale divisions on the meter may be in any suitable unit of length, depending upon the sensitivity of the meter and the circuit, and upon the desired full scale range of measurement.

I claim:

1. An electrical gauge comprising a tubular housing having an opening therein, an annular member secured in one end of said housing, a pair of spaced parallel elongated bars each secured at one end to said annular member, an iron core carried by one bar, a coil encircling a portion of said core, an armature carried by the other bar and normally engaging said core, a sleeve carried by the outer end of said first bar, and a pin slidably mounted in said sleeve to bear against the opposite bar at one end, the other end of said pin projecting through said housing opening.

2. An electric gauge comprising a rigid annulus, having opposed longitudinal grooves, a pair of spaced elongated bars each secured at one end in one of said grooves, a core carried by one bar spaced from said annulus, a coil encircling a portion of said core, a rigid guide carried by the outer end of said bar, an armature carried by the other bar in cooperative relation to said core, and a pin shiftable carried by said guide and engageable with said last named bar.

3. An electric gauge as defined in claim 2 wherein said parts constitute a preformed unit, and a housing for said unit having a tubular portion snugly receiving said annulus.

4. An electric gauge comprising a rigid support, an elongated bar secured at one end to said support, a core mounted on said bar, a coil encircling at least a portion of said core, a rigid guide carried by the free end portion of said bar and extending transversely thereof, an elongated resilient arm secured at one end to said support and extending in spaced relation to said bar, an armature carried by said arm in cooperating relation to said core, and a pin slidably carried by said guide and engageable with the free end of said arm.

5. An electrical gauge comprising a pair of spaced elongated bars, bar mounting means interposed between said bars at one end thereof, a core positioned between said bars and carried by one bar, a coil encircling at least a portion of said core, a transverse guide positioned between said bars and carried by the free end portion of said last named bar, a pin slidable in said guide and engageable with the other bar at one end and projecting laterally outwardly from said first bar at its opposite end, an armature carried by the other bar in cooperative relation to the core, a housing having an opening receiving the laterally projecting end of said pin, and means securing said mounting means to said housing.

6. An electrical gauge comprising a pair of elongated bars, means secured to said bars at one end thereof to mount said bars in spaced relation, a core carried by the inner face of one bar, a coil at least partially encircling said core, a transverse guide carried by the inner face of said last named bar, a pin slidably carried by

said guide with one of its ends projecting laterally outwardly from said last named bar and the other end engaging the other bar, an armature cooperating with said core, a mounting member secured to said armature and including a pin, the other bar having an opening in which said last named pin fits loosely, and solder in said opening encircling said last named pin.

10. An electrical gauge comprising a mounting member, an elongated bar secured at one end to said member, a guide carried by the free end of said bar and extending perpendicular thereto, a pin slidably mounted by said guide, a retainer on said pin engageable with said guide to limit movement of said pin in one direction, a core carried by said bar adjacent said guide, a coil encircling a portion of said core, a second bar secured at one end to said member and extending in spaced relation to said first bar and engageable by said pin, and an armature carried by said second bar and cooperating with said core.

25. An electrical gauge comprising a housing, a mounting member secured in said housing, a pair of spaced elongated bars each secured at one end to said mounting, an inductance unit carried by one bar and including an armature carried by the other bar, and means slidably carried by the free end of one bar and engageable with the other bar for laterally deflecting the latter, said housing having an opening through which said deflecting means projects.

30. An electrical gauge as defined in claim 8 35 wherein said deflecting means includes a portion positioned between said bars and a projecting portion detachably connected therewith.

40. An electrical gauge comprising a mounting member, a pair of elongated bars each secured at one end to said mounting member in spaced relation, a variable inductance unit having cooperating parts carried by opposite bars, deflecting means slidably carried by one bar and engageable with the other bar, said member, 45 bars, inductance unit and deflecting means constituting a unit, a housing receiving said unit and fixedly supporting said mounting member, and a contact member projecting from said housing and detachably connected to said deflecting means.

50. An electrical gauge comprising a rigid mounting member, a pair of spaced bars each secured at one end to said mounting, a variable inductance unit having cooperating parts carried by opposite bars, deflecting means slidably mounted on one bar and engageable with the other bar, and a housing having a portion fitting around said mounting, and an opening through which a portion of said deflecting means projects.

60. An electrical gauge comprising a rigid mounting member, a pair of spaced bars each secured at one end to said mounting, a variable inductance unit having cooperating parts carried by opposite bars, deflecting means slidably mounted on one bar and engageable with the other bar, a housing having a portion fitting around said mounting and an opening through which said deflecting means projects, and means for adjusting the position of said bars in said housing.

GEORGE L. GARVIN.
